UNITED STATES PATENT OFFICE.

ALBERT BOECLER, OF MALMO, SWEDEN, ASSIGNOR TO BENZINE CONDENSATION CO. INC., A CORPORATION OF NEW YORK.

MACHINE FOR APPLYING SOLUTIONS OF RUBBER OR THE LIKE TO FABRICS.

1,422,822.

Specification of Letters Patent. Patented July 18, 1922.

Application filed September 13, 1920. Serial No. 409,969.

To all whom it may concern:

Be it known that I, ALBERT BOECLER, a subject of the German Republic, residing at Malmo, Sweden, have invented certain new and useful Improvements in Machines for Applying Solutions of Rubber or the like to Fabrics (for which I have filed an application in Germany, Apr. 14, 1914), of which the following is a specification.

10 This invention relates to machines for applying solutions of rubber or similar material to fabric webs, or to impregnate such webs with solutions of rubber or similar material. In machines of this kind it is of importance to recover the solvents of such rubber, particularly benzine. The working table of such machines is enclosed in a casing, which in its lower part is constructed as a cooling mantle, or provided with cooling serpentine.

Such devices have proved to work well once the apparatus has started to work. However, such starting has been found to be difficult. This event can be explained by the fact that 25 as soon as an interruption of the working takes place, the drying or working table is cooled and, therefore, the casing will be filled with cold vapours of the solvent. Such vapours have throughout the same specific 30 gravity, and since on starting the apparatus the newly evaporated benzine will be warmer and, therefore, have a less specific gravity, these vapours will not be in a position to crowd away the cooler and therefore heavier 35 vapours accumulated below, and therefore cannot reach the cooling device. The same drawback will take place, though not to the same extent, when the lower part of the casing is filled with air.

0 To a certain degree the drawbacks mentioned above could be avoided by opening doors at the lower part of the casing when the machine is started to work. This, however, will have the disadvantage that the 5 vapours will emerge into the atmosphere.

According to the present invention the drawbacks mentioned above, will be avoided by giving opposite parts of the casing different temperatures. This will cause a circulation within the casing which will automatically set in as soon as the heating surface becomes warm, without necessitating the action of mechanical means, such as ventilators or the like. The downward flow of the benzine vapours now will only take place on one

side of the working table, while on the other side of the table the vapours will flow upwards.

In the drawing, in which is shown by way of example a machine for the above stated purpose, Figure 1 is an elevation of the machine constructed according to the invention. Figure 2 is a cross section and Figure 3 a plan of the machine. Figure 4 is an elevation of a modification partly in section, and Figure 5 a section of the modification shown in Fig. 4.

The casing enclosing the working table *a* consists of a lower part *c* and an upper part provided with doors or flaps *h* and windows *k*. An outlet *d* is provided at the lowest point of the casing for allowing condensed benzine to escape from the casing. The part *c* of the casing now comprises either a single chamber as shown in Fig. 2, or several chambers as shown in Fig. 5. In the first instance only on one side an outlet *f* need be provided for the cooling water entering at *e*. If, however, it is preferred to arrange also on the other side an outlet *f'*, there will be a difference in the cross sections of the two outlets so that the cooling water will flow through one with less velocity than through the other. The consequence of this is that on the part of the casing between *f* and *e*, if outlet *f'* has the greater cross section there will be a greater cooling effect than between *e* and *f'*. In the example shown in Fig. 2 the circulation will take place in an anti-clockwise direction, because the vapours that arise above the table *a* will at once flow to the left hand cooling surface projecting above the table and will hereby be cooled, and as far as these vapours are not condensed they will flow along the surface downwards. When they reach the lowest point, they will by that time be heated to a certain extent, and therefore the uncondensed vapours will flow upwards on the right hand side, and thus enter again the space above the working table *a*.

100 The condensation is so violent that there is a possibility to restrict the cooling of the lower part of the casing to the extent of a fraction of the length of the table.

105 It may be found preferable to make that part of the casing which is to be cooled in three sections, by which it will be possible to extend the lateral walls to the ceiling or cover of the casing. This modification is shown in Figures 4 and 5. The front part 110

a' of the casing may be of the usual construction. However, the central part *b'* of the cooling casing proper consists of the three sections *c'*, *d'*, *e'*. The lateral walls 5 *c'* and *e'* are extended up to the cover or ceiling *f'*. By these means the vapours which arise from the impregnated web *g°* will be cooled above the table *h'* on the side walls so that they will quickly run down along 10 the latter. Hereby the circulation will be essentially improved. Owing to the fact that the casing is made in three sections, it will be much easier to erect the casing on the machine. The lateral walls *e'* and *c'* are 15 constructed independently from the bottom *d'* hollow or double, and the connection of the bottom with the side walls is carried out by pipes *i*. The inlet pipe *k'* of the cooling liquid is arranged only on one side so 20 that the wall *c'* will be cooler than the wall *e'*, thus arranging so that the two longitudinal side walls of the casing will have different temperatures. The rubber solution, as is usual in machines of this description, is filled into the funnel *a°*, below which 25 the fabric *g°* is drawn along in the casing, as is well known in machines of this description. After traveling over the table *a* or *h'* horizontally, it passes around the roll 30 *g'* and then is drawn again horizontally below the table *a* or *h'* and leaves the casing at *g°*, where it is guided by the roll *g³* and is finally reeled up by the roll *g⁴*, which is rotated by the usual driving mechanism. 35 The roller *g'* is journaled within a prolongation *b²* of the casing *b'*, which prolongation is provided with cooling jackets *d²* similar to those provided in the casing *b'*.
I claim:
40 1. A machine for applying to fabric webs or impregnating fabric webs with solutions of rubber or similar material, comprising a working table and a casing, provided with cooling means on its lower part, the cooling
45 means being so constructed and arranged that the rate of flow of the cooling medium through different portions of the casing will not be uniform whereby the lateral walls of the casing will be cooled at different temperatures.
50 2. A machine for applying to fabric webs or impregnating fabric webs with solutions of rubber or similar material, comprising a working table and a casing, provided with cooling means on its lower part, the cooling

means being so constructed and arranged that the rate of flow of the cooling medium through different portions of the casing will not be uniform whereby the lateral walls of the casing will be cooled at different 60 temperatures, the cooling walls being made hollow or double.

3. A machine for applying to fabric webs or impregnating fabric webs with solutions of rubber or similar material, comprising 65 a working table and a casing, provided with cooling means on its lower part, the cooling means being so constructed and arranged that the rate of flow of the cooling medium through different portions of the 70 casing will not be uniform whereby the lateral walls of the casing will be cooled at different temperatures, the cooling part of the casing constructed in three sections, two of these forming the lateral walls and one 75 the bottom, each of which being constructed hollow or double independent from one another, and pipes to connect the lower parts of the side walls with the hollow space of the bottom, outlets on the upper 80 part of the side walls, and an inlet pipe on the bottom arranged to one side of the centre line.

4. A machine for applying to fabric webs or impregnating fabric webs with solutions of rubber or similar material, comprising 85 a working table and a casing, provided with cooling means on its lower part, the cooling means being so constructed and arranged that the rate of flow of the cooling 90 medium through different portions of the casing will not be uniform whereby the lateral walls of the casing will be cooled at different temperatures, the cooling part of the casing constructed in three sections, 95 two of these forming the lateral walls and one the bottom, each of which being constructed hollow or double independent from one another, and pipes to connect the lower parts of the side walls with the hollow space 100 of the bottom, outlets on the upper part of the side walls, and an inlet pipe on the bottom arranged to one side of the centre line, the lateral hollow walls extending up to the top of the casing.

ALBERT BOECLER.
